UNITED STATES PATENT OFFICE.

ACHILLE BATAILLE, OF NEW YORK, N. Y.

METAL DOOR OR GATE.

SPECIFICATION forming part of Letters Patent No. 448,314, dated March 17, 1891.

Application filed April 21, 1890. Serial No. 348,774. (No model.)

To all whom it may concern:

Be it known that I, ACHILLE BATAILLE, a citizen of the United States, residing in the city and State of New York, have invented 5 an Improvement in Metal Doors or Gates, of which the following is a specification.

In elevators for buildings and in warehouses gates have been made use of that are composed of parallel bars crossing each other and 10 pivoted at the intersections and known as "lazy-tongs gates;" but these gates are not well adapted to separating one portion of a warehouse from another, as they do not prevent the passage of fire.

15 Doors have been made of sheet-iron upon iron frames; but these doors are heavy and require considerable space for opening and closing, and in instances where such doors are fitted to slide they require a large recess in 20 the wall or a space for movement equal to their own width, and these conditions often cannot be obtained in buildings. Besides this the doors become warped in cases of fire and bind in their frames in such a manner 25 that they cannot be opened.

My present improvements are for combining with the lazy-tongs gates or doors metal slats that are attached to the lazy-tongs and move with them, and in opening and closing 30 the doors the slats slide one upon another and overlap to a greater or less extent, and the lazy-tongs door or gate provided with these metal slats occupies but little more space when it is open than the ordinary lazy-tongs 35 gate, and the sheet-metal slats can be made to entirely close the doorway and form a fire-proof door, or they can occupy only the lower portion of the doorway in cases where it is desired to have the upper portion of the doorway open; or the sheet metal can be perforated 40 with ornamental openings in cases where the portions of the slats do not require to be plain sheet metal.

In the drawings, Figure 1 is an elevation 45 of the gate complete with portions of the intersecting bars removed to show the connections to the slats. Fig. 2 is a plan view in section at the line xx , and Fig. 3 is a sectional plan view below the line yy , representing the 50 slats as slipped one over the other when the door is opened.

The doorway is of any desired size or char-

acter, and in the same is the sill-rail A, usually in the form of a trough, and there is a lintel-guide B for the top of the door, and at 55 C is the door-jamb, against which the door closes, and D is a door jamb or post to which the lazy-tongs are partially connected, the parallel crossing bars of such lazy-tongs being shown at E and pivoted together at their 60 intersections, and F is the vertical bar at the moving edge of the door.

The lazy-tongs gate is pivoted at 2 to the post D, and the rivets or bolts 3 slide in slots in the upper and lower portions of the post 65 D, and the connection between the lazy-tongs bars E and the vertical bar F is made by the rivets 4, which form pivotal connections, and the rivets or bolts 5 in slots in the upper and lower portions of the vertical bar F, and it is 70 usual to provide a roller 6 at the lower end of the vertical bar F, resting upon the sill-rail A to support the gate or door as it is opened or closed.

The gate thus far described is to be of any 75 desired size or character, and it corresponds generally with lazy-tongs gates that have heretofore been made use of.

The metal slats are of any desired height and width. They may extend from the sill-rail A to the lintel-guide B and slide at top and bottom in such rails, or the slats may only extend a portion of the distance vertically in the doorway, and such metal slats may be plain or perforated to a greater or less 85 extent, and when perforated the openings may form ornamental designs. Each slat is stiffened by flanges or corrugations running vertically and lengthwise of the same. I have shown flanges 7 and corrugations or 90 ribs at 8, and I have shown four of these sheet-metal slats; but the number may be more or less. Each slat is permanently connected with the lazy-tongs bars at or near one of its edges. The slat nearest the moving 95 edge of the door is permanently connected to the vertical bar F, so that it moves with the same. The other sheet-metal slats are connected at the intersections of the lazy-tongs bars permanently by the rivets 9 to form 100 pivots for the lazy-tongs bar and are in line with the pivots 2 and 4, and upon the slats G are slide-guides 10 and 11 above and below the pivotal connections 9 and in line with the

same, and in these slide-guides 10 and 11 are pivot blocks or studs 12, connected with the pivot bolts or rivets at the intersections of the lazy-tongs bars. When the door is closed 5 in the doorway, the slats G lap upon each other slightly at the adjacent edges, and as the door is opened and the crossing bars of the lazy-tongs gate come nearly parallel to each other the sheet-metal slats G can slip 10 bodily one over the other and assume the position shown in Fig. 3, and they do not interfere with the opening or closing of the lazy-tongs gate, and when such gate is opened 15 the slats may occupy the same space width-wise as the folded lazy-tongs bars, and if the number of metal slats is less and the slats are wider such slats may project at their free edges past the vertical post D into a recess in the wall adapted to receive them; or in cases 20 where the door-post D is pivoted at the top and bottom, as is frequently the case in this class of doors, and as shown in Patent No. 358,956, granted March 8, 1887, the lazy-tongs door and the slats may be swung upon such 25 post D into a position at right angles to that occupied by the door when closed.

It is to be understood that the slide-guides 10 and 11 for the pivot-blocks 12 need not occupy more space than the lazy-tongs bars 30 when folded together. Hence the addition of the sheet-metal slats does not permit the lazy-tongs door or gate being actuated in the ordinary manner and shutting up as closely as usual.

35 The metal slats are sometimes made either partially or wholly of open-work—such as strips of sheet metal or wires interwoven and supported by suitable frames or borders—and these slats are preferably placed at slightly-40 increasing distances from the plane of the lazy-tongs bars, so as to allow one slat to slide over the other and remain parallel to the gate or door.

I am aware that in metallic shutters the 45 metal slats have been fitted with crossing or lazy-tongs bars to raise or lower them and

maintain their parallelism; but in this case the edges of the metal slats are turned toward each other to form hooks that intervene between one slat and the next, and thereby 50 the slats stand diagonally to the plane of movement of the lazy-tongs, and they necessarily occupy a much greater space when brought together in opening the shutter than they would if the surfaces of the sheets of 55 metal coincided. In my improvements these difficulties are avoided, and the metal slats slide closely one against the other.

I claim as my invention—

1. The combination, with the lazy-tongs 60 door or gate, of metal slats lapping one upon the other and having flanges on their edges turned toward the lazy-tongs and pivotal connections against the flanges for the lazy-tongs bars, substantially as set forth. 65

2. The slats G, having flanges at one edge and stiffening-ribs at the other edge and the flat surfaces contiguous to each other, in combination with the lazy-tongs door or gate, the attaching-pivots 9, and the slide-guides upon 70 the metal slats against the flanges and the pivot blocks or studs contiguous to the intersections of the lazy-tongs door or gate and within the slide-guides, substantially as set forth. 75

3. The lazy-tongs door or gate, the post D, to which the same is connected, and the vertical bar F at the moving edge of the lazy-tongs door, in combination with the metal slats G, having flanges at their edges and the 80 flat surfaces lapping upon and against one another, and one of which slats is connected to the vertical bar F, the slide-guides 11 upon the slats and against the flanges, the pivots for the lazy-tongs, and the pivot blocks or 85 studs within the slide-guides, substantially as set forth.

Signed by me this 16th day of April, 1890.
ACHILLE BATAILLE.
